M. E. MALLO.
CARBURETER.
APPLICATION FILED SEPT. 25, 1915.

1,193,580.

Patented Aug. 8, 1916.

UNITED STATES PATENT OFFICE.

MICHAEL E. MALLO, OF GREELEY, COLORADO.

CARBURETER.

1,193,580.

Specification of Letters Patent. Patented Aug. 8, 1916.

Application filed September 25, 1915. Serial No. 52,604.

To all whom it may concern:

Be it known that I, MICHAEL E. MALLO, a citizen of the United States, residing at Greeley, county of Weld, and State of Colorado, have invented certain new and useful improvements in Carbureters; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in carbureters more especially intended for use in connection with internal combustion engines used on automobiles or motor vehicles, my object being to provide an article of this class which shall be of simple and economical construction, reliable, durable and efficient in use.

Having briefly stated the objects of my invention, I will proceed to describe the construction of the same in detail, reference being made to the accompanying drawing, in which is illustrated an embodiment thereof.

In this drawing, Figure 1 is a vertical section taken through the carbureter on the line 1—1, Fig. 2. Fig. 2 is a top plan view of the construction or a view looking in the direction of arrow 2, Fig. 1. Fig. 3 is a top plan view in detail showing the lever and the valve controlled thereby for regulating the entrance of gasoline to the float chamber, being a view looking in the direction of arrow 3, Fig. 1. Fig. 4 is a section taken on the line 4—4, Fig. 1.

The same reference characters indicate the same parts in all the views.

Let the numeral 5 designate a casting which forms the casing of the carbureter, the same comprising a member 6 inclosing the float chamber 7; a member 8 inclosing the carbureting chamber 9, an air inlet member 10 at the bottom; and an outlet 12 at the top through which the explosive mixture passes to the manifold (not shown).

The bottom of the casing member 6 is provided with a threaded opening 13 into which is screwed a tube 14 whose opening 15 is eccentrically arranged. The bottom of this tube is provided with a relatively small port 16 through which the liquid passes to the float chamber, its entrance however being controlled by the cone-shaped

extremity 17 of a valve 18 which extends longitudinally through the passage 15 being provided with a number of longitudinal grooves 19 which form passages for the liquid. The upper extremity of the valve 18 protrudes into the float chamber 7 and is provided with a reduced neck 20 which is engaged by the slotted end of a small lever 21, the valve having an enlargement or head 22 at the upper extremity of the neck forming a stop for the forks 23 of the lever which are arranged on opposite sides of the neck 20. This lever is fulcrumed on the upper extremity of the tube 14, a pin 24 constituting the fulcrum, said pin passing through openings formed in lugs 25, which openings register with an opening of corresponding size formed in the lever. Beyond the fulcrum in a direction opposite the valve extends an arm 26 of the lever and which is engaged by a projection 27 formed on the bottom of a float 28 located within the chamber 7. The upper extremity of the tube 14 is cut away below the lever as shown at 29, to allow the lever the necessary movement to lift the valve 18 and open the port 16 to allow the liquid to enter the float chamber, when the liquid is sufficiently low to allow the float to act upon the lever for the purpose. The upper extremity of the float chamber is closed by a screw cap 30.

A relatively small passage 31 connects the bottom of the float chamber 7 with a recess 32 formed in a boss 33 extending upwardly from the bottom of the casing member 8. The upper portion of this recess is threaded as shown at 34 to receive the lower threaded end of a small nozzle 35 which extends upwardly into the carbureting chamber and into which protrudes the upper part 36 of a needle valve 37 which is threaded into the boss below the bottom of the recess and passes through a screw 38 which acts upon a packing 39 to form a tight joint. The lower extremity of this needle valve is exposed and equipped with a milled head 40 to facilitate adjustment. The upper extremity of the nozzle 35 is cone-shaped and terminates in a relatively small exit port 41, the upper end 42 of the needle valve being of counterpart shape to regulate the passage of gasoline into the carbureting chamber. This carbureting chamber is closed at the top by a screw cap 42 which carries a depending annularly arranged perforated wall 43 having a conform member 44 extending upwardly from

its lower edge; this member being smallest at the top and whose opening surrounds the upper extremity of the nozzle 35. The lower end of this coniform frustum-shaped member is open to receive the air which enters through the inlet chamber 10 which is in communication with a chamber 45 located between the lower extremities of the two chambers 7 and 9, the chamber 45 however 10 communicating with the chamber 9 by way of an opening 46 which leads to the bottom opening of the member 44. This last named member extends upwardly into the perforated wall 43 its upper extremity terminating 15 some distance above the lowermost perforations of this wall, the latter being surrounded by an annular space within the chamber 9. The upper part of the chamber 9 is open as shown at 47 whereby the carbureting chamber communicates with an auxiliary chamber 48 which in turn is in communication with the outlet 12 through which the explosive mixture passes to the manifold.

20 As shown in the drawing the passage through the air inlet member 10 is controlled by a disk valve 49 mounted on a stem 50 to which is attached a manipulating handle 51. The passage through the outlet member 12 is 25 controlled by a similar valve disk 52 equipped with a handle 53 to facilitate manipulation. The lower portion of the perforated wall 43 is provided with an exterior flange 54 which fits closely within the lower part of the carbureting chamber and practically prevents the air from passing upwardly around the perforated wall before it passes into and through the space inclosed by said wall.

From the foregoing description the use 30 and operation of my improved carbureter will be readily understood. The gasolene or other liquid used in forming the explosive mixture enters the tubular member 14 through the port 16 and passes thence into 35 the chamber 7 of the casing member 6 and continues to enter this chamber until the float is raised high enough to relieve the valve 18 and allow the latter to seat itself. The liquid flows through the passage 31 into 40 the nozzle 35 and thence upwardly through the opening 41 at the upper extremity of said nozzle. The air enters through the inlet member 10 and flows around the nozzle 35

and facilitates the breaking up of the liquid as it leaves the opening 41. The circulation of the air also forms a partial vacuum around the nozzle 35 and facilitates the drawing of the liquid from this nozzle and into the chamber surrounded by the perforated wall, 43. In this chamber the air and liquid are 45 combined to form the explosive mixture which flows through the perforations of this wall, into the auxiliary chamber 48, and thence through the outlet member 12 into the 50 manifold (not shown).

Attention is called to the fact that the axes of the casing members 6 and 8 are so located that a plane cutting the same longitudinally will lie parallel with a plane passed longitudinally through the axes of all the cylinders of an engine with which the carbureter may be used. Furthermore the air inlet member 10 and the outlet member 12 for the explosive mixture are situated between the casings 6 and 7 on opposite sides, one extending below and the other above. By reason of this construction the carbureter may be located within a comparatively small space and for this reason this peculiar construction and arrangement is exceedingly advantageous.

Having thus described my invention, what I claim is:—

A carbureter comprising a carbureting chamber, a liquid-containing chamber communicating with the said carbureting chamber, a nozzle located in the carbureting chamber and in communication with the passage connecting the two chambers, a cap closing the top of the said carbureting chamber and provided with a depending annularly arranged perforated wall having a coniform frustum-shaped member extending upwardly from its lower edge, this member being smallest at the top and whose opening surrounds the upper extremity of the nozzle, a valve in the latter, and means for regulating the valve to control the passage of liquid to the carbureting chamber.

In testimony whereof I affix my signature in presence of two witnesses.

MICHAEL E. MALLO.
